UNITED STATES PATENT OFFICE

JAMES FAIRHEAD, OF TORONTO, ONTARIO, CANADA

ELEVATOR-DUMPING DEVICE

Application filed February 28, 1929. Serial No. 343,454.

This invention relates to improvements in elevator dumping devices, as described in the present specification and illustrated in the accompanying drawings which form 5 part of same.

The invention consists essentially of the novel features pointed out broadly and specifically in the claims for novelty following a description containing an explanation in 10 detail of an acceptable form of the invention.

The objects of the invention are to construct an elevating dump bucket in which the operation of dumping the load is simplified and made automatic; to economize in 15 the expenditures of time and labour occupied in elevating and dumping a given quantity of material; to reduce the power required to operate the elevator by shortening 20 the distance of travel and emptying nearer the pile, thus preventing crushing and dust, especially in the unloading of coal and coke, the effect of the drop being eliminated by dumping or unloading the bucket at a very 25 slight elevation above the pile; to eliminate the necessity of lowering the coal onto the pile by way of tricklers or chutes commonly used when the coal is lowered any distance from the top of the storage bin; to empty 30 the elevating bucket at any convenient position in the path of its travel; and generally to provide an elevating dump bucket, simple and durable in its constructional features and efficient in operation.

35 In the drawings, Figure 1 is a plan view of the invention.

Figure 2 is a vertical sectional view showing the unloading mechanism in operation.

40 Figure 3 is a detail section view of the unloading doors in their closed position.

Figure 4 is a diagrammatic elevational view of this invention in operation.

45 Figure 5 is a front elevational view of the bucket.

Figure 6 is a front elevational view showing the bucket in its unloading position.

Like numerals of reference indicate corresponding parts in the various figures.

50 In most mechanisms in use at the present time for elevating and unloading coal into

storage bins or silos in coal yards, it is necessary to elevate the coal to the top of the bin or silo before allowing it to fall into same. The coal is usually lowered from the top of the bin or silo by way of tricklers or opposed chutes. An objection to this method is that considerable time and power is required to elevate the coal to the top of the bins before dumping, and a considerable amount of coal is broken or ground up in this way, resulting in undesirable coal dust. In my invention it is necessary to only elevate the bucket to a distance slightly beyond the top of the pile of coal in the bin, when the bucket automatically opens to deliver the coal into a hopper and thence to the bin or silo at this level by way of a chute, thus eliminating the necessity of tricklers and greatly reducing the time required in elevating and unloading.

Referring to the drawings, the numeral 10 indicates a rectangular receptacle or bucket having end walls 11, the front wall 12, the rear wall 13, and the slanting bottom 14. The bucket is reciprocally mounted in a vertical frame 22 consisting of the front corner posts 23 and the rear corner post 24. The corner posts 23 and 24 are preferably situated at the ends of the bucket and the front corner posts 23 are so arranged that they will project slightly beyond the front wall 12 of the bucket, as at 23A.

Vertical cleats or strips 25 are secured on each end wall 11 and adjacent each corner. The cleats 25 lie in a groove 26 formed by the undercut strip 27 secured to the corner posts 23 and 24. The cleats 25 are adapted to reciprocate in the groove 26 as the bucket is raised or lowered in the framework 22 and serves to retain the bucket 10 in its proper path. A rectangular opening 29 is formed in the lower portion of the front wall 12 and extends to a point as at 30 adjacent each end. Guide plates 30A are situated at each of the front corners to prevent the material from collecting in the corners and to guide the material to the opening 29 when the bucket is being dumped or emptied. A door 31 is hingedly mounted to the wall 12 at its upper edge as at 32.

The door 31 is adapted to swing by its own weight and close the upper portion of the opening 29. A second door 33 is pivotally mounted at its lower edge to the floor 14 of the bucket 10 and adjacent the front edge thereof as at 34. The door 33 in its closed position closes the remaining portion of the opening 29 and has extensions or cleats 35 secured adjacent its upper edge and extending therebeyond adapted to bear on the outer side of the door 31 and retain said door in its closed position. Angles or tracks 36 are secured to the portion 28A of each front corner post 23. Rollers 37 are rotatably mounted at each end of the door 33 and are adapted to bear against the angles or tracks 36 and retain said door 33 in its closed position. At each point where it may be desired to dump or unload the bucket 10, a gap 40 is formed in the tracks or angles 36. At the upper end of each section of track 36 between each gap 40, the track 36 is bent outwardly as at 41 to form a guide 42 which serves to guide the roller 37 back to the track 36 when the bucket is lowered below the gap 40.

Thus, when the bucket 10 is raised to this position, the door 33 with the roller 37 pivots about the hinge 34 to an open position with the door 33 in line with the slanting floor 14. In this position the material in the bucket will empty through the opening 29 forcing the door 31 to swing outwardly to an open position. After the bucket is emptied, the door 31 swings to a closed position and as the bucket is lowered below the gap 40, the rollers 37 take a position bearing against the angles or tracks 36 and force the door 33 to a closed position. 45 40 is a hopper into which the material is dumped from the bucket 10. An apron or chute 46 is situated in the upper side of the hopper 45 and adjacent the gap 40. The door 33 when it swings open at this position, rests on the apron 46 as at 47 and any material in the bucket 10 is carried by way of the door 33 and apron 46 into the hopper 45. A vertical flange 46A is formed at each side of the apron 46 to prevent the material from spilling over the sides of the apron. For the purpose of closing any of the gaps 40 so that the bucket 10 may be elevated above this point without emptying, a door 55 48 pivotally mounted at its upper edge as at 49 adjacent the lower end of the next section of track 36, carries a strip 48A adjacent each side thereof which falls in line with the tracks 36 when said door 48 is in its closed position so that the rollers 37 on coming to a gap 40 closed by the door 48 will bear on the strips 48A until it reaches the next section of track 36 above the gap 40.

65 In Figure 4 I show the unloading bucket

in operation. 50 are silos or bins in which it is desired to store coal or the like. The framework 22 in which the buckets are raised or lowered is located adjacent the silos 50.

In this case I show two buckets with their respective framework 22 in operation and serving two silos or bins each. With this arrangement, when one bucket is being raised by the winding mechanism as indicated at 51, the other bucket is being lowered by the same winding mechanism. Thus each bucket balances the other and the lifting mechanism 51 need only act to lift the load in either of the buckets and to overcome friction. 70 75 80

At each point where it may be desirable to empty the bucket 10, the hopper 45 is situated and a gap 40 is formed in the tracks 36 and a gap door 48 is mounted to close each gap when desired. A pivoted spout or chute 52 is mounted under each hopper 45 and is adapted to lead into adjacent openings 53 formed in each bin 50 and at this level. Thus by means of the pivoted spout or chute 52, the coal or other material may be delivered at the openings 53 in either of the silos 50. 90

What I claim is:

An elevator dumping device having 95 means for elevating same and comprising a rectangular bucket opened at the top and having an opening in the lower portion of one side, a slanting floor in said bucket converging towards said side opening, a door hingedly mounted above said side opening and adapted to swing by its own weight and close a portion of said opening, a second door hingedly mounted at the bottom of said bucket and adapted to swing to a closed position over the remaining portion of said opening and having extensions at its upper edge adapted to overlap said first named door, a vertical frame consisting of four corner posts suitably braced and forming a reciprocal mounting for said bucket, a projecting track on adjacent sides of two of said corner posts situated adjacent said side opening in said bucket, rollers rotatably mounted on the outside of said second named door and adapted to bear against said projecting track to retain said door in its closed position, gaps in said tracks at predetermined spillway positions, bent portions at the upper end of each length of track forming a guide adapted to receive and guide said rollers back to said tracks when said bucket is lowered below the position for emptying at any of said spillways, and pivoted doors at each of said spillways adapted to pivot to a closed position and lengths of track secured thereon positioned to bridge said gaps. 100 105 110 115 120 125

Signed at the city of Toronto, this 13th day of February, 1929.

JAMES FAIRHEAD.
